UNITED STATES PATENT OFFICE.

THEODORE COLEMAN, OF NEW YORK, N. Y.

SOFA-BEDSTEAD.

SPECIFICATION forming part of Letters Patent No. 283,210, dated August 14, 1883.

Application filed January 16, 1883. (No model.)

To all whom it may concern:

Be it known that I, THEODORE COLEMAN, a citizen of the United States, residing at New York, in the county and State of New York, have invented new and useful Improvements 5 in Sofa-Bedsteads, of which the following is a specification.

This invention relates to that class of sofa-bedsteads in which the seat-frame is arranged 10 to be lifted off the main frame and deposited on the floor without turning; and it consists in the novel means hereinafter described for connecting the seat-frame to the main frame.

This invention is illustrated in the accompanying drawings, in which Figure 1 is a perspective view, showing the seat-frame lifted off the main frame. Fig. 2 is a vertical cross-section when the seat-frame is adjusted upon the main frame.

20 Similar letters indicate corresponding parts.

The letter A designates the main or sofa frame, and B the seat-frame, which may be provided with head-pieces, as usual. Upon the bottom of the seat-frame A is fitted a mattress, 25 which is divided longitudinally into two sections, C C', which are connected together by hinges o in such a manner that the section C is adapted to be folded upon the section C', the latter being fixed to the main frame next 30 to the back D. The seat-frame B is connected on the inner edge with the folding section C of the mattress by hinges s, which are so arranged that when the seat-frame is placed in position on the main frame the folding section C is thereby swung over upon the fixed

section C', as shown in Fig. 2, while, when the seat-frame is lifted off the main frame and deposited on the floor, the folding section is brought to the position shown in Fig. 1, flush with the fixed section C' and the top of the 40 seat-frame. Said folding section thus produces the proper connection between the seat-frame and main frame, and at the same time forms a part of the bed which is obtained when the seat-frame is lifted off the main frame. Both 45 sections C C' of the mattress are provided with a suitable filling, and beneath the same on the main frame are arranged springs f to co-operate therewith. The seat-frame, moreover, is upholstered in any usual or suitable 50 manner to produce the appearance of a sofa or lounge when it is adjusted on the main frame.

What I claim as new, and desire to secure by Letters Patent, is—

The combination, substantially as hereinbefore described, of the main frame, the seat-frame, and the mattress divided longitudinally into two sections, one of which is fixed to the main frame and the other hinged to both said 60 fixed section and the seat-frame, for the purpose specified.

In testimony whereof I have hereunto set my hand and seal in the presence of two subscribing witnesses.

THEODORE COLEMAN. [L. s.]
